UNITED STATES PATENT OFFICE

148,323

DESIGN FOR A HANDBAG OR SIMILAR ARTICLE

Irving Pichel, New York, N. Y.

Application June 17, 1947, Serial No. 139,755

Term of patent 7 years

(Cl. D87—3)

To all whom it may concern:

Be it known that I, Irving Pichel, a citizen of the United States of America, residing in New York, county of New York, and State of New York, have invented a new, original, and ornamental Design for a Handbag or Similar Article, of which the following is a specification, reference being had to the accompanying drawing, forming part thereof.

Fig. 1 is a side perspective view of a handbag or similar article showing my new design.

Fig. 2 is a front perspective view of the handbag in open position; the handles of the bag being broken away for convenience of illustration.

I claim:

The ornamental design for a handbag or similar article, substantially as shown and described.

IRVING PICHEL.
